LOUIS J. GOLDEN, OF CHICAGO, ILLINOIS, ASSIGNOR TO B. & B. SHOE COMPANY, OF CHICAGO, ILLINOIS, A CORPORATION OF ILLINOIS

DESIGN FOR A CARTON OR SIMILAR CONTAINER

Application filed February 13, 1931. Serial No. 38,644. Term of patent 3½ years.

To all whom it may concern:

Be it known that I, LOUIS J. GOLDEN, a citizen of the United States, and resident of Chicago, in the county of Cook and State of Illinois, have invented a new, original, and ornamental Design for a Carton or Similar Container, of which the following is a specification, reference being had to the accompanying drawing, forming a part thereof.

Figure 1 is a perspective view of a carton showing my new design, the decoration being omitted because of the size of the figure and being shown on a large scale in the other figures.

Figure 2 is an enlarged view of the side of the container shown in Figure 1, said view showing the decoration provided for said side, the decoration shown in Figure 2 being the same for both sides of said container.

Figure 3 is a view of the blank forming the front and top of the container shown in Figure 1 and showing on a large scale the decoration provided thereon;

Figure 4 is a view of the bottom of the container shown in Figure 1 and showing on a large scale the decoration provided thereon; and

Figure 5 is a view of the rear of the container shown in Figure 1, and showing on a large scale the decoration provided thereon.

I claim:

The ornamental design for a carton or similar container, substantially as shown and described.

Signed at Chicago, in the county of Cook, and State of Illinois, this 17th day of January, A. D. 1931.

LOUIS J. GOLDEN.
